UNITED STATES PATENT OFFICE.

JOHN WILLIAM PIPPIN, OF OKLAHOMA, OKLAHOMA, ASSIGNOR TO PIPPIN MANUFACTURING COMPANY, OF OKLAHOMA, OKLAHOMA, A CORPORATION OF OKLAHOMA.

UNDERREAMER.

1,322,337.

Specification of Letters Patent. Patented Nov. 18, 1919.

Application filed January 29, 1919. Serial No. 273,786.

To all whom it may concern:

Be it known that I, JOHN W. PIPPIN, a citizen of the United States, and a resident of Oklahoma city, in the county of Oklahoma and State of Oklahoma, have invented 5 certain new and useful Improvements in Underreamers, of which the following is a specification.

My invention is an improvement in underreamers and has for its object to provide a device of the character specified, wherein the cutting bits are so mounted that they may be held in contracted position during the insertion of the reamer by latch mechanism, 10 which is released when the bits are passed through the casing to permit them to expand, wherein the bits are so mounted that they will be firmly braced and held during the cutting action, and wherein means 15 is provided for shielding the connection of the bits with the body to prevent the entrance of sand, gravel and the like.

In the drawings:

Figure 1 is a side view of the improved 20 underreamer;

Fig. 2 is a longitudinal section showing the parts in inoperative position;

Fig. 3 is a similar view showing the parts 25 in operative position;

Fig. 4 is a perspective view of a portion 30 of the upper end of the bit;

Fig. 5 is a similar view of the latch bar;

Figs. 6, 7 and 14 are sections on the lines 35 6—6, 7—7 and 14—14 respectively, of Fig. 2;

Figs. 8 and 13 are sections on the lines 40 8—8 and 13—13, respectively, of Fig. 3;

Fig. 9 is a perspective view of the sleeve;

Fig. 10 is a perspective view of one of the 45 reinforcing plates;

Fig. 11 is a side view of the lower end of the mandrel, with parts in section;

Fig. 12 is a section on the line 12—12 of 50 Fig. 11.

In the present embodiment of the invention, the body 1 of the tool is provided at 55 its upper end with a tapering threaded stem 2 for engagement by the operating mechanism for the tool, and the body is longitudinally bored at its lower end. This bore

50 or recess is flared at the lower end of the body, and the supporting rod or mandrel 3 for the bits is arranged within the bore or recess, the said bore or recess being of considerably greater diameter than the rod, 55 as shown.

At its lower end a cross head 4 is detachably connected with the mandrel in a manner to be presently described, and this cross head supports the bits 5. Each of the bits 5 is provided with a tapering portion above 60 the cross head, and each of these tapering portions is separated from the body of the bit by shoulders 6 and 7, respectively. Each bit has a transverse recess 8 for receiving the cross head 4, and it will be noticed that 65 each bit has a longitudinally extending groove 9 on its inner face, extending from the recess 8 to the top of the bit and of greater depth toward the top than at the recess 8 as shown, for receiving the mandrel 3.

The mandrel has an enlarged portion or head 10 just above the cross head 4, and this head has a transverse opening through which extends a key 11, the said key being 70 locked from transverse movement in a manner to be presently described, and the key supports a sleeve or housing 12 which fits about the body at the lower end. The sleeve is mounted to slide on the body moving with 75 the mandrel 3, the said body being annularly reduced at its lower end to permit its sliding movement. The body also has longitudinally extending slots 13 in which the ends of the key move, and the sleeve is strengthened and reinforced at the openings for the ends of the key by means of the reinforcing plates, shown more particularly in Fig. 10. Each of these plates which fit upon the inner face of the sleeve has an 80 opening or slot 15 for engagement by the end of the key, and the ends of each plate at the outer face thereof are ribbed transversely, as shown at 16. These ribs engage circumferential slots in the sleeves. 85

The bits and mandrel are normally forced upward by means of a coil spring 17 which encircles the mandrel between stops arranged within the body of the tool and upon the rod or mandrel. The stop 18 100 upon the mandrel is a nut threaded thereon, and having a washer below the same, while the stop 19 in the body is a collar which encircles the rod or mandrel and is feathered thereon, as shown, by means of a key 20 105 in the collar engaging a keyway or groove in the rod. This collar is annularly grooved, as shown in Figs. 2 and 3, and the groove is adapted to be engaged by a pin 21 which is passed transversely through an open- 110

ing in the body. The ends of the pin are engaged by the sleeve 12 to prevent displacement thereof.

The mandrel is releasably held from upward movement under the influence of the spring by means of a latch bar 22, shown more especially in Figs. 2, 3, 4 and 5. This bar fits within a longitudinally extending opening 24 in the body communicating with the bore or recess, and at its upper end the bar has an inwardly extending lug 25 which has a slotted opening 26 for receiving a pivot pin 27 which pivotally connects the latch bar to the body. The lug 25 extends inwardly beyond the peripheral surface of the bore or recess and slidably engages a longitudinally extending slot 28 in a sleeve 29 which is mounted on the upper end of the rod or mandrel for a purpose to be presently described.

A plate spring 30 engages the latch bar below its pivotal connection and normally acts to swing the lower end of the bar inwardly. This spring, as shown, is held in a groove in the body, the groove having undercut side walls. This spring, as shown, tapers from above downward and the groove is similarly formed so that it cannot drop downward below a predetermined point. Near its upper end it has an opening for engagement by a tool to permit the removal of the spring.

On its inner face and near its upper end the latch bar has a transverse undercut recess 31, and within this recess is held a substantially triangular bar 32, with the apex of the bar extending beyond the latch bar and providing a cam for coöperating with a similarly shaped tooth or cam 33 on the lower end of the sleeve 29. This sleeve fits loosely about the upper end of the rod just above the nut 18, normally resting upon this nut, and while the mandrel will not move upwardly without moving the sleeve it may move downwardly without affecting the sleeve.

When the latch bar is in the position of Fig. 2, with the bits collapsed, that is, with the mandrel and the bits in lowered position, the tooth or cam 33 is below the tooth or cam 32, and if the latch bar is prevented from outward movement at its outer end the sleeve will be held from upward movement and will in turn hold the mandrel and the bits from upward movement. During the insertion of the tool, while the tool is in the well casing, the engagement of the latch bar with the well casing prevents the outward movement of the latch bar to release the interengaging cams 32 and 33. As soon, however, as the latch bar passes below the lower end of the well casing the latch bar is forced outward at its lower end, the cams 32 and 33 disengaged, and the sleeve, the rod or mandrel and the bits move up-

ward into the position of Fig. 3, that is, into operative position.

In withdrawing the tool from the casing it is merely drawn upward. At their lower ends the bits have transverse shoulders 34, which are engaged by the lower end of the well casing, and further upward movement of the tool will cause the bits and the mandrel to be drawn downwardly against the resistance of the spring 17. The drawing downward of the bits will collapse them as shown in Fig. 2, into position such that they may move through the well casing. The sleeve being free from the mandrel, will not interfere with this downward movement of the mandrel, because of the engagement of the teeth or cams 32 and 33.

In order to center the tool in the casing during its movement longitudinally thereof, the latch bar has a longitudinally extending spacing rib 35 on its outer face, the said rib extending beyond the body when the latch bar is in normal position, and spacing the tool from the casing the depth of that portion of the rib which extends beyond the body. A facing rib or plate 36 is arranged at the opposite side. This rib, which is tapering or wedge shaped, is held within a groove 37 in the body of the tool, the said groove gradually increasing in depth from above downward, and the groove has undercut side walls, as shown more particularly in Fig. 13.

The bar may be adjusted in the groove to extend any desired distance beyond the body, and when in proper position may be locked by upsetting the walls of the groove or calking them downward upon the rib. The key 11 is locked to the head of the mandrel, by means of a pin or rod 38 which extends longitudinally in a bore in the lower end of the rod, the said bore extending from the lower end into the opening. As shown in Fig. 12, the lower end of the bore for the pin or rod 38 is enlarged at its lower end as at 39, the enlargement being tapering or funnel shaped and having a shoulder at its lower end.

A plate spring 40 is secured to the rod or pin, and the lower end of this spring is bent out to engage this shoulder. An opening 41 is provided in the rod or mandrel at the shoulder for permitting the insertion of a tool to release the end of the spring from the shoulder. When the spring is forced inwardly the pin or rod may be withdrawn, thus releasing the key 11. The pin 27, which pivots the latch bar to the body, is prevented from slipping out in either direction by means of plates 42. These plates are received in undercut grooves 43 extending longitudinally of the body at the ends of the rod. It will be noticed, referring to Fig. 11, that the cross head 4 is braced against the mandrel and reinforced by sub-

stantially triangular webs 44, and the bits are recessed to receive these webs when the bits are in operative position. The tapering or enlargement of the lower end of the bore 5 of the body has inclines or cut away portions 45 at the point where the upper ends of the bits engage, so that the said upper ends will slip easily into and out of operative position.

10 To introduce the improved tool into the well casing, it is necessary that the parts occupy the position of Fig. 2. In order to move them into this position the body has a transverse slotted passage 46 at the upper 15 end of the bore or recess, and this passage is adapted to receive a wedge plate 47. The wedge plate, when it is forced into the passage, engages the upper end of the sleeve, forcing the sleeve down together with the 20 mandrel and the bits and puts the spring 17 under tension. As soon as the tool is in the well casing to the level of the latch plate, the wedge plate may be withdrawn, and it is provided with a ring 48 for permitting 25 the easy withdrawal.

I claim:

1. An underreamer comprising a cored body, a rod slidable longitudinally of the body and having a cross head at its lower 30 end, bits having openings for receiving the ends of the head and pivoted to the head with a lost motion connection to permit the bits to move bodily toward the rod, a spring normally pressing the rod upwardly, the 35 body having a lateral opening, a latch plate pivoted in the opening and provided with an inwardly extending catch lug, a sleeve slidable on the upper end of the rod and having a catch lug for engagement below 40 the lug of the plate to hold the rod downward, the rod having a stop for limiting the downward movement of the sleeve, the sleeve being freely movable upward, and means in connection with the lower end of 45 the body and the bits for expanding the bits when the rod is moved upwardly.

2. In an underreamer, a body having openings in its lower end, substantially semi-circular in cross section, the straight walls 50 of the openings being approximately parallel and the outer curved walls being inclined, bits having portions shaped to fit the openings, a rod slidable in the body and to which the bits are pivotally connected, normally active means forcing the rod upward to cause the said bit portions to enter the openings to expand the bits, the body having a lateral opening, a latch plate pivoted to the body in the opening and having a lug 55 extending into the body, a sleeve mounted to slide on the rod and having a lug for engaging beneath the lug of the plate to hold the rod in downward position with the bits contracted.

60 3. In an underreamer, a body having a

bore flaring at the lower end of the body, a rod movable in the body, bits pivoted to the rod and having portions fitting the flaring part of the bore to hold the bits expanded, the bore having a lateral opening, 70 a latch plate pivoted to the body in the opening, a sleeve movable on the rod, the rod having a stop for limiting the downward movement of the sleeve, and the sleeve and plate having interengaging means for holding the rod in lowered position, said means comprising catch lugs on the plate and sleeve and beveled on both faces for the purpose specified.

4. In an underreamer, a body having a 80 bore flaring at the lower end of the body, a rod movable in the body, bits pivoted to the rod and having portions fitting the flaring part of the bore to hold the bits expanded, the bore having a lateral opening, a latch 85 plate pivoted to the body in the opening, a sleeve movable on the rod, the rod having a stop for limiting the downward movement of the sleeve, and the sleeve and plate having interengaging means for holding the rod 90 in lowered position, and means in connection with the sleeve and the plate for preventing outward swinging movement of the free end of the plate when the rod is in upward position.

95 5. In an underreamer, a body having a bore flaring at the lower end of the body, a rod movable in the body, bits pivoted to the rod and having portions fitting the flaring part of the bore to hold the bits expanded, the bore having a lateral opening, a latch plate pivoted to the body in the opening, a sleeve movable on the rod, the rod having a stop for limiting the downward movement of the sleeve, and the sleeve and plate having interengaging means for holding the rod 100 in lowered position.

105 6. In an underreamer, a body having a longitudinal bore at its lower end provided with a lateral opening, a rod in the bore and carrying bits at its lower end, the bits and body having means for expanding the bits when the rod is moved upward, a spring acting normally to move the rod upward, a latch plate in the lateral opening, and co-operating means on the latch plate and rod for holding the rod against the action of the spring when the plate is pressed inward, said means being movable upward with respect to the rod and held from downward 110 movement.

115 7. In an apparatus substantially as described, in combination with the bits mounted to expand and contract, of a supporting rod for said bits, a spring operating said rod in one direction, a sleeve, said sleeve being freely movable in an opposite direction to that of the operating rod spring, and a latch co-operating with said sleeve.

120 8. The combination with an apparatus 125

- substantially as described, of a body portion, a supporting rod in the said body portion, a spring for operating said rod in one direction, a sleeve encircling a portion of the 5 rod and freely movable in a direction opposite to the spring actuation of the supporting rod, means on the rod abutting the sleeve for limiting its movement in the opposite direction, a latch coöperating with the sleeve 10 for holding the rod against movement under the influence of the spring, and bits carried by the supporting rod, substantially as set forth.
9. A reamer comprising bits, a body portion socketed in its lower end to the bits, a 15 supporting rod connected with the bits and extending within the body, a sleeve on the rod, an abutment on the rod for engaging the sleeve, a spring for actuating the rod in one direction, said sleeve being freely movable in another direction, a latch coöperating with the sleeve and carried by the 20 body, substantially as set forth.
10. The combination in a reamer, of a body portion, a bit-supporting rod, a sleeve 25 abutting the rod and movable in one direction independently of the rod, and a latch engaging said sleeve.
11. A reamer substantially as described, comprising a body portion, bits carried 30 thereby, a supporting rod for the bits, a latch for holding the supporting rod in extended position to permit the bits to be contracted, and means for engagement by 35 the latch to hold the rod with the bits contracted and movable independently of the rod in the other direction whereby the latch will not interfere with the extension of the supporting rod in the withdrawal of the 40 bits.
12. The combination in a reamer, of a body portion, longitudinally movable bits carried thereby, means whereby the bits may be held in contacted position during the 45 insertion of the reamer through the casing and embodying latch mechanism, said latch mechanism being normally held in operative position by the well casing and being released when the bits have passed through 50 the well casing to permit the bits to expand, and means in connection with the bits for engagement by the latch mechanism and independent of any movement of the bits in one direction, whereby the bits may be contracted for withdrawal without operating 55 the latch mechanism.
13. The combination, in an apparatus substantially as described, of a body portion, a supporting rod in the said body portion, a 60 spring for operating said rod in one direction, a sleeve encircling a portion of said rod, means on the rod abutting the sleeve, said sleeve being freely movable in a direction opposite to the spring actuation of 65 the supporting rod, a latch coöperating with said sleeve for holding the rod against movement by the spring, bits carried by the supporting rod, and a sleeve encircling the body and extending beyond the lower end of the same and encircling the upper ends 70 of the bits and movable with the bits.
14. A reamer comprising a body portion socketed in its lower end for the bits, a supporting rod connected with the bits and extending within the casing, a sleeve on the 75 rod, an abutment on the rod for engaging the sleeve, a spring for actuating the rod in one direction, said sleeve being freely movable in another direction, a latch coöperating with the sleeve and carried by the 80 body, substantially as set forth.
15. A reamer comprising a body portion 85 socketed in its lower end for the bits, a supporting rod connected with the bits and extending within the casing, a sleeve on the rod, an abutment on the rod for engaging the sleeve, a spring for actuating the rod in one direction, the sleeve being freely movable in another direction, a latch coöperating with the sleeve and carried by the 90 body, substantially as set forth.
16. A reamer comprising a body portion 95 socketed in its lower end for the bits, a supporting rod connected with the bits and extending within the casing, a sleeve on the rod, an abutment on the rod for engaging the sleeve, a spring for actuating the rod in one direction, the sleeve being freely movable in another direction, a latch coöperating with the sleeve and carried by the 100 body, substantially as set forth.
17. The combination in a reamer, of a body portion, a bit-supporting rod, a sleeve abutting the rod and movable in one direction independently of the rod, a latch engaging said sleeve, bits connected with the 105 rod, and a sleeve on the body and connected with the rod for housing the junction of the body and the bits.
18. The combination in a reamer, of a body portion, a bit-supporting rod, a sleeve abutting the rod and movable in one direction independently of the rod, a latch engaging said sleeve, and a housing for the lower end of the body portion and movable 110 with the rod.
19. The combination in a reamer, of a body portion, a bit-supporting rod, a sleeve abutting the rod and movable in one direction independently of the rod, a latch en- 115
- 120
- 125
- 130

- gaging said sleeve, said latch having a spacing rib for centering the body portion in a well casing, said body portion having a spacing bar at the opposite side of the bit and
 5 adjustable radially of the body portion, said bar being wedge shaped and being movable longitudinally of the body portion, said body portion having a groove provided with an inclined bottom in which the bar moves.
- 10 20. The combination in a reamer, of a body portion, a bit-supporting rod, a sleeve abutting the rod and movable in one direction independently of the rod, a latch engaging said sleeve, said latch having a spacing rib for centering the body portion in a well casing, said body portion having a spacing bar at the opposite side of the bit and
 15 adjustable radially of the body portion.
21. The combination in a reamer, of a body portion, a bit supporting rod, a sleeve abutting the rod and movable in one direction independently of the rod, a latch engaging the said sleeve, and means in connection with the latch and with the body
 20 for centering the body portion in a well casing, the means on the body portion being adjustable.
22. The combination in a reamer, of a body portion, a bit supporting rod, a sleeve abutting the rod and movable in one direction independently of the rod, a latch engaging the said sleeve, a spring moving the rod in the said direction, said body portion having a transverse opening at the
 25 upper end of the sleeve and a wedge movable through the opening for pressing the sleeve and rod in opposition to the spring.
23. The combination in a reamer, of a body portion, a bit supporting rod, a sleeve abutting the rod and movable in one direction independently of the rod, a latch engaging the said sleeve, a housing extending beyond the lower end of the body portion and connected with the rod to move there-
 30 with, said connection comprising a key extending transversely of the rod and engag-
 35 ing the sleeve at its ends, the body portion having slots for the said ends, a detachable
- connection between the key and rod, said connection comprising a pin movable longitudinally of the rod at the axis thereof, the key having an opening for engagement by the pin, and means for locking the pin from withdrawal.
24. The combination in a reamer, of a body portion, a bit supporting rod, a sleeve abutting the rod and movable in one direction independently of the rod, a latch engaging the said sleeve, a housing extending beyond the lower end of the body portion and connected with the rod to move there-
 40 with, said connection comprising a key ex-
 45 tending transversely of the rod and engag-
 50 ing the sleeve at its ends, the body portion having slots for the said ends, and a detachable connection between the key and the rod.
25. The combination in a reamer, of a body portion, a bit supporting rod, a sleeve abutting the rod and movable in one direction independently of the rod, a latch engaging the said sleeve, a housing extending beyond the lower end of the body portion and connected with the rod to move there-
 55 with.
26. The combination in a reamer, of a body portion, a bit-supporting rod, a sleeve abutting the rod and movable in one direction independently of the rod, a latch engaging said sleeve, and a spring for pressing the latch outward, substantially as set forth.
27. In an apparatus substantially as described, in combination with the bits mounted to expand and contract, of a supporting rod for said bits, a spring operating said rod, in one direction, a sleeve, said sleeve being freely movable in an opposite direction to that of the supporting rod spring, a latch coöperating with said sleeve, and a spring between the latch and the rod.
